UNITED STATES PATENT OFFICE.

FRANK F. FORSHEE, OF MANSFIELD, OHIO, ASSIGNOR TO WESTINGHOUSE ELECTRIC & MANUFACTURING COMPANY, A CORPORATION OF PENNSYLVANIA.

THERMOSTATIC SWITCH.

Application filed May 20, 1928. Serial No. 110,359.

My invention relates to thermostatic switches and more particularly to thermostatic switches used to control the temperature of sad irons and other electrically heated devices.

An object of my invention is to provide a simple, efficient thermostatic switch which shall have relatively few parts and may be readily manufactured at a low cost.

10 Another object of my invention is to provide simple means in such a device to produce a substantial separation between relatively movable contacts with only a slight deflection of the thermostat.

15 Another object of my invention is to provide, in a device of the above-indicated character, a lever having a member secured thereto for bridging a plurality of contacts, which lever has a loose, pivotal connection with its support, thus insuring an efficient electrical connection between the contacts in the bridging member under all conditions of operation, even though the bridging member has been deformed on account of arcing 25 or otherwise.

20 Another object of my invention is to provide simple, efficient means to hold the thermostatic disc in its proper operative position.

25 Another object of my invention is to provide a simple means for connecting the thermostat with the member supporting the movable contact.

30 Other objects will be apparent from the disclosure.

The present embodiment of my invention comprises a supporting plate having lugs to hold a thermostat in spaced relation to the plate. A pair of contact members, each having an electrical connection to a terminal member, are mounted on the plate. These contact members are normally electrically connected through a bridging contact member mounted on a lever which is loosely pivoted to the supporting plate. A stud, that is secured to the thermostat and that passes through a hole in the supporting plate, has means thereon to loosely engage the lever to operatively connect the lever 45 with the thermostat.

In the drawing,

Fig. 1 is a top plan view of a thermostatic switch embodying my invention.

Fig. 2 is a side elevational view of the switch shown in Fig. 1; and

Fig. 3 is a sectional view, taken on the line III—III of Fig. 1.

Referring to the drawing, a metallic supporting plate 10 which may, of course, be of any desired shape, (but is here shown as circular) has integral lugs 11 extending substantially at right angles thereto. Each of the lugs 11 is provided with a shoulder 12 which serves to maintain a bimetallic thermostatic disc 13 in spaced relation to the plate. To retain the thermostatic disc in that position, any suitable means may be used, but, in the present instance, the lugs are deformed so as to produce slight projections which bear against the bottom of the disc.

An opening 14, herein shown as elongated, is provided in the plate and receives one arm 15 of an L-shaped lever 16, the other arm of which normally is substantially parallel to the plate, as best shown in Fig. 3. The portion of the arm 15, that extends through the opening 14 is preferably reduced in width to provide shoulders 17 to limit the extent to which the arm 15 will extend 20 through the opening. The area of the opening 14 is somewhat larger than the cross-sectional area of the reduced portion of the arm 15, thus providing a loosely pivoted connection. The arm 15 may be bent, as at 25 18, to retain it in the opening.

Near the other end of the lever is provided a bridging contact member 19 that may be secured in place by any desired means, such as a rivet 20. The bridging 30 member and the rivet may be insulated from the remaining structure by any desired means, such as mica sheets 21. This bridging member normally rests against, and electrically connects, two contact members 22, each contact member resting on a flat conductor 23. Each conductor is connected, at its opposite end, with a terminal post 24 which is provided with a screw 25 for the purpose of securing a conductor to the post. 35 The contact members 22 and the conducting bars 23 may be insulated from the plate by means of mica sheets 26 and are secured to the plate by suitable means, such as rivets 27.

A stud 28 is secured to the thermostatic 40 disc, preferably at its center, by means of

any suitable securing means, such as nuts 29. The stud 28 extends through an opening 30 in the supporting plate 10. This stud passes through an opening 31 provided in the lever 16. The openings 30 and 31 are made somewhat larger than the stud 28.

Means are provided on the under side of the lever and mounted on the stud for operatively engaging the lever upon operation of the thermostat. A convenient form of such means is herein shown as a nut 32, which is locked in position by a nut 33. On the upper side of the lever, a nut 34, or other securing means, may be provided to maintain the lever 16 in operative position. A lock nut 35 may be provided to lock the nut 34 in position. The lever 16 may be made of a metallic channel strip, thus providing strengthening flanges 36.

At ordinary temperature, the thermostat and other movable parts are in the positions shown in full lines in Fig. 2 and Fig. 3. In this position, electric current from a conductor (not shown) will pass from one terminal post 24 through the corresponding conductor 23 and contact member 22, the bridging contact member 19, the opposite contact member 22 and the corresponding conductor 23 to the terminal post 24.

When the temperature of the surrounding medium rises above a certain point, the thermostat will operate to raise the stud 28 which, in turn, will raise the lever 16 by means of the nut 32. Since the lever is pivotally connected to the supporting plate at 14, only the outer end, which bears the contact bridging member, will be raised. This, of course, breaks the electrical connection between the two contact members 22.

Since the lever is loosely pivoted to the supporting plate 14 and since the nuts 32 and 34 do not closely engage the lever 16, it is obvious that the bridging contact member 19 will, at all times, engage the contact 22 when the device is in horizontal position, as shown in the drawing. If the lever were

not loosely pivoted to the supporting plate, as in my invention, and the breaking contact member 19 were deformed, on account of arcing or from any other cause, the bridging contact member might only engage one contact so that no current would flow.

While I have herein illustrated and described a preferred form of my invention, it is obvious that the invention may be otherwise utilized and, therefore, I do not wish to be limited to such specific form or otherwise except as defined by the appended claims.

I claim as my invention:

1. A thermally actuatable switch comprising a supporting plate having an opening, a thermostat supported by said plate, a lever of L-shape, one arm of said lever being normally parallel to said plate and having an insulated bridging contact member on its outer end, the other arm having its end portion loosely and pivotally fitting in said opening, a lost-motion connection between said thermostat and said lever and positioned intermediate said opening and said bridging contact member, and a pair of insulated contact members on said plate and normally electrically connected through said bridging contact member.

2. A thermally actuatable switch comprising a supporting plate having an opening, a thermostat supported by said plate, a lever of L-shape, one arm of said lever being normally parallel to said plate and having an insulated bridging contact member thereon, the other arm having its end portion loosely and pivotally fitting in said opening, said lever being operatively connected with said thermostat, and a pair of insulated contact members on said plate and normally electrically connected by said bridging contact member.

In testimony whereof, I have hereunto subscribed my name this 17th day of May, 1926.

FRANK F. FORSHEE.
